UNITED STATES PATENT OFFICE.

GEORGE HALL WHITE, OF WASHINGTON, DISTRICT OF COLUMBIA, ASSIGNOR TO
GEORGE P. SACKS, OF BRADLEY HILLS, MARYLAND.

ICE-CREAM MACHINERY.

Application filed April 16, 1921. Serial No. 462,068.

This invention relates to an improvement in ice cream machinery and particularly to a means whereby an accurate and predetermined weight of mix may be delivered to the freezer.

It has been heretofore proposed to provide means whereby a predetermined volume of mix may be delivered to the freezer, the patent to A. R. Sanna, No. 1,351,302, issued 10 August 31, 1920, being an example of this type of device. With the production of a substantially uniform mix, devices of the patented type referred to are effective in accurately controlling the quantity of mix for 15 delivery to the freezer. Experience has demonstrated however, that it not infrequently happens that there is a difference in the characteristics delivered in successive charges of the device due primarily to the 20 fact that each successive charge of the device from the original mix or batch is appreciably lighter in weight for the same volume than the preceding charge owing to the continued aeration of the batch. Of course, it is well 25 understood that the batch from which the mix control device receives its successive charges is being continually aerated, and hence the weight per unit volume of the first charge from such batch will be appreciably 30 greater than the weight per unit volume of the less charge from such batch. As the type of devices for controlling the mix delivery to the freezer as herein before referred to have been governed entirely by 35 volume, it follows that in those cases where there is a difference in weight per unit volume of successive charges, that some of the charges will be of greater than necessary solid content, while others of such charges 40 will be of less than necessary weight content. In the commercial manufacture of ice cream, the authorities have limited the minimum proportion of solid content, and it is entirely possible that some of the charges of the 45 volume controlling device will be less than such minimum solid content. It follows necessarily that where continued aeration exists in the batch that practically no two successive charges of the volume controlling device will be of the same weight content, and hence as it is desired that all charges be of 50 substantially the same weight content, it is of importance that the mix charge be governed by weight rather than by volume.

Therefore the essential object of the pres-

ent invention is to provide a means for insuring that the proportion of weight content of each successive mix charge to the freezers will be substantially the same, and this without regard to the quantity of material used, 60 or more exactly that for a given mix charge, the weight of the solids shall be in each instance substantially that required by the health authorities.

It has been heretofore proposed to govern 65 the discharge of liquids or semiliquids through an apparatus automatically controlled by the weight of the liquid, and while the general principle heretofore proposed is contemplated in the present apparatus, such 70 present apparatus is adapted by specific improvements for the handling of an ice cream mix. These improvements may be briefly characterized as a manual means for releasing the content of the weighing receptacle 75 into the freezer and to combine with this means, a locking element, whereby the commodity receptacle will be held in proper discharging relation to the freezer until the discharge means has been closed to cut off communication between said receptacle and 80 freezer. This permits the single operator to take care of a number of mix control devices as having once established communication between the commodity receptacle and the 85 freezer, such communication is maintained until a positive cut off of this communication is had by a direct act of the operator. Thus through a simple movement, the operator may connect the successive mix control devices with the freezers and need give 90 them no further attention until a full discharge is had.

Furthermore the invention contemplates a 95 specific valve construction involving a manually adjustable member, whereby the normal valve stem may be lengthened at will. This provides for maintaining an accurate and desired relation between the end of the valve stem and the commodity receptacle in the 100 event the supply pipe should for any reason be inaccurately placed. Thus within limits, the proper operation may be secured between the receptacle and valve by adjusting the valve stem to compensate for any irregularity of relative positions. Also, by the adjustment described, the valve may be permitted to cut off at different levels of the commodity receptacle, in order to thereby 105 provide for a variation in the volume within 110

the receptacle independently to a certain extent of the weight of the material within said receptacle. Thus the valve may be adjusted to close immediately following the initial movement of the receptacle after receiving the predetermined weight of material, or may be set to close at substantially any other position of the receptacle beyond such minimum valve closing position, so that any predetermined increase of volume, within the limits of the valve adjustment, may be had additionally to that volume required to make up the predetermined weight.

In the drawings:

Fig. 1 is a broken perspective view showing the improved mix control device in locked and discharging relation with a freezer.

Fig. 2 is a similar view with the mix control device in normal or mix receiving position.

Fig. 3 is an enlarged broken elevation showing the combined valve and locking means.

Fig. 4 is an enlarged elevation partly in section showing the valve for automatically cutting off the supply of mix to the commodity receptacle.

As will be apparent from the drawing and following description, there is to be provided with each freezer 1, a mix control device to which the mix is delivered from the aerator or mixer through a pipe 2 primarily controlled by a manually operable valve 3.

The mix control device of this invention includes a scale beam 4 pivotally supported at 5 in standards 6 rising from the freezer 1 or from a base as 7 removably or otherwise secured to the freezer. One end of the scale beam is forked providing arms 8, on which through knife trunnions 9, is supported a commodity receptacle 10. The receptacle, as will later appear, is designed for limited movement only, and in such movement is guided within uprights 11 rising from the base 7 and positioned to compel movement of the receptacle in substantially the same plane at all times. The scale beam 4 is movable beyond the pivot 5 and a guide 12 rising from the freezer 1 or other appropriate support and having a forked upper end 13 to which the scale beam is guided. Beyond the guide 12, the beam is suitably scaled at 14 and provided with a weight 15 slidably adjustable to vary the weight in the usual manner.

The discharge receptacle 10 has an outlet 16 leading from its lowest point thereof to and through a pipe 17 carried by and movable with the receptacle, which pipe has a depending discharge section 18 adapted when the receptacle is in its lowermost position, to enter an opening 19 formed in the freezer 1. The opening 19 is preferably sur-

rounded by an upstanding hollow boss in order that the receptacle discharge may be in communication with the freezer notwithstanding slight variations in the position of the receptacle. The discharge pipe section 17 is provided with a valve for controlling the flow therefrom, which valve of any ordinary type or construction, is designed for manual operation through a handle 20. The handle carries a locking rod 21 which extends outwardly from the valve handle and depends into a position adjacent the discharge end of the pipe, being provided at its lower end with an inturned projection 22. The boss surrounding the opening into the freezer 1 is provided with an exterior lug 23 beneath which the projection 22 of the locking rod 21 is adapted to engage. The position of the lug 23 is such that the projection 22 will engage beneath said lug when the valve handle is turned toward and into open position, so that as the valve is opened to permit the passage of the material from the receptacle 10 into the freezer, the projection 22, riding beneath the lug 23, will lock the receptacle to the freezer, and hence maintain the receptacle and freezer in this predetermined relation until released by the closing of the valve handle 20.

The feed pipe 2 depends below the valve 3 to position within the commodity receptacle 10, the lower end of this pipe extension, indicated at 24, terminating some distance above the lowermost or discharge position of the commodity receptacle. The lower end of the feed pipe extension 24 is provided with a valve 25 operating preferably from within the pipe and seated against the valve seat 26 formed at the lower end of the pipe to close the discharge end of the pipe. The valve 25 has the usual extension 27 projecting through the discharge opening of the pipe to guide the valve in movement and is additionally formed with a stem 28 on which is adjustably mounted an auxiliary stem 29. The stem 29 is slidably connected to the stem 28 as by a slide collar 30, and may be set in adjusted positions lengthwise the stem 28 by a set screw 31 carried by the collar 30 and engaging the stem 28.

With the parts arranged as shown particularly in Fig. 2, it will be noted that the weight 15 overbalancing the receptacle causes the latter to move upwardly and to engage the stem 28 of the valve or the auxiliary stem if the latter has been adjusted to project below the stem 28, and therefore open the valve 25. The valve 3 having been previously opened, the material will find its way from the batch mixer into the commodity receptacle 10, and will continue to flow until the predetermined weight, indicated by the adjustment of the weight element 15 on the scale beam, has been delivered to the receptacle 10. As the receptacle overbalances,

it will move downwardly until finally positioning the discharge pipe within the opening to the freezer. The downward movement of the commodity receptacle is necessarily to an extent to move below the possible limit of the valve stem 28 or auxiliary stem 29, in order to thereby permit the valve 25 to be closed, both by its own weight and by the weight of the material behind it in the pipe, to cut off the further discharge of material into the receptacle 10. The operator desiring to charge the freezer, opens the valve by manipulating the handle 20 and simultaneously with and as an automatic result of the opening of such valve, locks the commodity receptacle to the freezer. This position will be maintained until the full contents of the commodity receptacle have been delivered to the freezer, as the commodity receptacle is locked in position, and cannot move upwardly notwithstanding diminution in weight due to loss of contents. The operator desiring a further predetermined weight of mix in the freezer simply closes the valve handle 20, thus releasing the receptacle which being overbalanced by the weight element 15, moves upwardly to again open the valve opening 25 and repeat the operation just described.

The advantage of the automatic locking means controlled solely in the movement of and through the position of the discharge valve handle is of importance, as it permits an operator to take care of a large number of machines as he may simply pass from one to another, locking the loaded commodity receptacles to the freezer and the discharge into the freezer will continue without further attention on his part, the requirement for additional material to the freezer being simply met by moving the valve handle 20 to a closed position, which releases the lock and permits the commodity receptacle to return to a charging position. Thus beyond the control of the valve 20, the device may be said to be completely automatic and to require no attention whatever on the part of the operator for an effective result.

The adjustable feature in connection with the valve 20 is of importance. It frequently happens that a mix of definite weight of solid content in one operation will have one volume while succeeding charges will have a slightly greater volume. It is apparent from the construction described, that the receptacle moves downwardly slightly before the predetermined weight of material is within the receptacle, for the reason that the receptacle will move a small distance before the valve 25 will be permitted to completely close. If now the unit volume of one mix charge is slightly heavier than a similar unit volume of a succeeding mix charge, it follows that a slightly greater proportion of material must be delivered

into the commodity receptacle in the lighter unit volume charge than in the heavier unit volume charge. Therefore, the valve 25 under these conditions cannot be permitted to close exactly the same volume of material after the receptacle has started its initial downward movement. Hence the adjustable valve is provided in order that where a lighter material per unit volume is handled, the valve may be held open for a slightly longer period following the initial downward movement of the commodity receptacle, so that the additional volume thus provided makes up the requisite weight.

It will be readily apparent from the above description, that the improved mix charge control device is governed entirely by weight and hence the solid content of each and every mix charge is substantially identical. Thus the due proportions of solids required by the health authorities can be introduced into each mix charge with absolute certainty and without substantial variation.

Claims:

1. The combination with an ice cream freezer of a mix control device including a receptacle and a scale beam to one end of which said receptacle is connected, a feed pipe leading into said receptacle, means controlled by the position of the receptacle for governing the supply from the feed pipe to the receptacle, a discharge pipe leading from the receptacle, a manually operable valve in said pipe, the freezer being formed with an opening to receive the discharge pipe when the commodity receptacle is depressed, and means operated in the opening movement of the manually operable valve when the receptacle is depressed to lock the receptacle to the freezer.

2. The combination with an ice cream freezer having an opening of a mix charge control device including a receptacle and a scale beam to one end of which said receptacle is connected, a discharge member from said receptacle cooperating with the opening in the freezer when the receptacle is in depressed position, a valve controlling said pipe, a locking rod movable with the valve and having a projection, and a lug carried by the freezer beneath which said projection is adapted to ride in the opening of the valve, whereby in the discharge of the material from the receptacle to the freezer said parts are locked against separation.

3. The combination with an ice cream freezer of a mix charge control apparatus including a scale beam having an adjustable weight at one end, a commodity receptacle at the other end of said beam, a discharge from said receptacle leading to the freezer, controlling means for said discharge, an automatic lock governed in the opening movement of the controlling means when the receptacle is depressed to relatively fix the

1 receptacle and freezer during the discharge, a material feed pipe leading within the receptacle, a valve controlling the outlet of said pipe, said valve being positioned to be 5 opened when the receptacle is in elevated position to admit a charge of material to said receptacle and permitted to assume closed position when said receptacle is in depressed position to cut off the supply of material, 10 and means for varying the operative length of the valve stem.

4. The combination with an ice cream freezer of a mix charge control apparatus including a scale beam having an adjustable 15 weight at one end, a commodity receptacle at the other end of said beam, a discharge from said receptacle leading to the freezer, controlling means for said discharge, an automatic lock governed in the opening 20 movement of the controlling means when the receptacle is depressed to relatively fix the receptacle and freezer during the discharge, a material feed pipe leading within the receptacle, a valve controlling said feed pipe 25 and having a depending stem adapted to be engaged by the receptacle in its upward movement to regulate the time of opening the valve in the movement of the receptacle, and means for adjusting the length of said 30 stem.

5. The combination with an ice cream freezer of a mix charge control apparatus including a scale beam having an adjustable weight at one end, a commodity receptacle 35 at the other end of said beam, a discharge from said receptacle leading to the freezer, controlling means for said discharge, an automatic lock governed in the movement of the controlling means to relatively fix the 40 receptacle and freezer during the discharge, a material feed pipe leading within the receptacle, a valve controlling the outlet of said pipe, said valve having a depending stem to cooperate with the bottom of the receptacle for the control of the valve in the 45 movement of the receptacle, said stem including an adjustable auxiliary stem.

6. The combination with an ice cream 50 freezer of a mix control device, including a receptacle responsive to a predetermined weight of material therein to move toward the ice cream freezer, a feed pipe for material to be delivered to the receptacle, means for preventing delivery of material 55 through the feed pipe as the receptacle moves toward the freezer, a manually operable valve for controlling the delivery of material from the receptacle to the freezer, and means operated in the opening movement of said 60 valve to hold the receptacle in discharge relation to the freezer.

7. The combination with an ice cream 65 freezer of a mix control device, including a receptacle responsive to a predetermined weight of material therein to move toward

the ice cream freezer, a feed pipe for material to be delivered to the receptacle, means for preventing delivery of material through the feed pipe as the receptacle moves toward the freezer, a manually operable valve for controlling the delivery of material from the receptacle to the freezer, and means operated in the movement of said valve in one direction to hold the receptacle in discharge relation to the freezer. 75

8. The combination with an ice cream freezer of a valve controlled feeding means for the material to be frozen, a receptacle movable from an operative receiving relation to the feeding means to an operative discharge relation to the freezer, a counter weight normally holding the receptacle in operative receiving relation to the feeding means, a predetermined weight of material in the receptacle overcoming said counter weight and moving the receptacle from an operative receiving relation to the feeding means to an operative discharge relation to the freezer, the valve controlled feeding means being automatically governed by and in the movement of the receptacle, manually operable means for interlocking the receptacle and freezer to hold the receptacle in discharge relation to the freezer and a valve controlling the discharge from the receptacle 80 to the freezer, said interlocking means and valve being connected for simultaneous movement to open the valve when the means is connected to interlock the receptacle and freezer, and to close the valve when the means is connected to disconnect the receptacle and freezer. 90

9. The combination with an ice cream freezer of a valve controlled feeding means for the material to be frozen, a receptacle movable from an operative receiving relation to the feeding means to an operative discharge relation to the freezer, a counter weight normally holding the receptacle in operative receiving relation to the feeding means, a predetermined weight of material in the receptacle overcoming said counter weight and moving the receptacle from an operative receiving relation to the feeding means to an operative discharge relation to the freezer, the valve controlled feeding means being automatically governed by and in the movement of the receptacle, a valve for controlling the discharge from the receptacle to the freezer and a manually operable locking member carried by the receptacle and adapted to engage and interlock the freezer to hold the receptacle in discharge relation to the freezer, said locking member and valve being connected to compel opening movement of the valve when the locking member is operated to function as such and a closing movement of the valve when the locking member is operated to disconnect the receptacle and freezer. 10

10. The combination with an ice cream freezer, of a movable material receptacle, means for normally holding the receptacle in a predetermined position, said receptacle moving from such predetermined position to an operative discharge relation to the freezer under a weight of contained material sufficient to overcome said holding means, means whereby material may be delivered to the receptacle when the latter is in such predetermined position, and means to be operated for holding the receptacle in discharge relation to the freezer at will, whereby the receptacle with a required weight 15 of material will move into discharge relation to the freezer and may be held in such discharge relation for any period wholly without regard to the absence of such material due to the discharge thereof into the 20 freezer.
11. The combination with an ice cream freezer, of a movable material receptacle, means for normally holding the receptacle in a predetermined position, said receptacle moving from such predetermined position to an operative discharge relation to the freezer under a weight of contained material sufficient to overcome said holding means, means whereby material may be delivered to 25 the receptacle when the latter is in such predetermined position, cut off means to be operated to control the delivery or non-delivery of the material from the receptacle to the freezer, and means operated in the operation of the cut off means for holding 30 the receptacle in discharge relation to the freezer while the cut off means is open and in releasing the receptacle from discharge relation to the freezer when the cut off means is closed. 35
12. The combination with an ice cream freezer, of a receptacle movably mounted on the freezer, means for feeding material to the receptacle, means for normally holding the receptacle in operative receiving relation 40 to the feeding means, a discharge conduit leading from the receptacle, said receptacle under a predetermined weight of material overcoming the holding means and moving to a position to arrange the discharge conduit in operative discharge relation to the freezer, a valve controlling said discharge conduit and means carried by the valve adapted when the valve is open to fix the receptacle in discharge relation to the 45 freezer and maintain it in such relation while the valve is open. 50
